VARIABLE DELIVERY PUMP OR MOTOR

Elek K. Benedek, Bucyrus, Ohio

Application October 24, 1934, Serial No. 749,745

12 Claims. (Cl. 103—161)

This invention relates to variable delivery pumps and motors of the radial piston type and has for its primary object the provision of a simple, efficient and hydrostatically balanced 5 pump.

Another object of the invention is the provision of novel piston actuating means whereby a two pumping cycle pump operation will be obtained, simultaneously allowing a stroke adjustment of 10 the pistons from zero to a predetermined maximum.

Another object of the invention is the elimination of rotary piston actuating means and the provision of high speed piston actuating devices 15 for high speed track mechanism, to thereby simplify the structure and the operation of the pump.

Another object of the invention is the provision of a unitary piston and double roller assembly, so arranged, that the rollers are capable of high 20 speed operation on their respective track members while they support the piston unit on specially arranged capillary anti-friction elements.

Another object of the invention is in the provision of novel cylinder barrel or rotor and hydrostatically balanced valve pintle assembly and 25 means for the lubrication of said assembly.

Further novelty of the invention lies in the provision of adjustable supporting means for said 30 rotor or cylinder barrel, to take up the wear between said rotor and the pintle and maintain a desirable clearance space therebetween for the purpose of limiting slip and obtaining sufficient lubrication for high speed bearing support.

Another object is in the provision of special 35 bearing surfaces in a casing, to adjustably support the piston reactance means and to removably secure said piston reactance means in the casing.

Another object is in the provision of a rigid 40 support for both ends of a main valve pintle.

Other more specific objects and advantages will appear from the description of an illustrative embodiment of the invention shown in the drawings.

In the drawings:

Fig. 1 is a partial transverse sectional view of the said embodiment of the pump, taken on the lines 1—1 in Figs. 2 and 3 respectively;

Fig. 2 is a longitudinal sectional view of the pump taken substantially along the line 2—2 in 50 Fig. 1, showing two sets of diametrically opposite pistons and their carrying rollers (turned 30° from their positions according to Fig. 1), the view being taken through the major axis of the stroke controlling cam or track assembly of the pump;

Fig. 3 is a longitudinal sectional view of the 55

pump, taken on line 3—3 in Fig. 1, through the minor axis of the stroke controlling cam or track assembly;

Fig. 4 is a transverse sectional view taken on the line 4—4 in Fig. 2, showing the variable stroke cam mechanism and the cooperative rollers in the maximum stroke position, the rollers being shown in elevation for clearness in illustration;

Fig. 5 is a transverse sectional view taken on the line 5—5 in Fig. 3, showing the variable stroke cam mechanism and the cooperating piston actuating rollers in their minimum stroke position;

Fig. 6 is an isometric perspective view of one 15 of the stationary parts of the variable stroke cam mechanism; and

Fig. 7 is a longitudinal fragmentary section taken on the plane of Fig. 2, showing the taper pintle and barrel and (diagrammatically) the 20 operative clearance therebetween.

The pump disclosed for illustration is enclosed in a generally cylindrical casing, comprising a cylindrical central main body section 10, having an integral end plate portion 10'' and a hub 25 portion 10'' projecting therefrom. The opposite end of the casing is closed by an end cover 11 rigidly secured to the open end of the main body section 10 and a smaller cover 12 secured to a circular flange of the cover 11 as by cap screws 14. A plurality of laminated shims 13 are provided as a bearing adjustment (to be later described) and are positioned between the parts 11 and 12.

The inner surface of the main casing is finished to form a continuous cylindrical surface as at 11 (Fig. 1) to form cooperative working surfaces with the piston operating cam assembly 43—43 and 46 respectively, as will be hereinafter described. The casing portion 10'' carrying the hub portion 10'', for the main pump connections, (not shown in the drawings) is provided with a central counter bore as at 10a to receive anti-friction bearing means 30, 31 and 32, and the hub portion 10'' is provided with central bore 10' to rigidly secure and receive an enlarged portion 15a of valve pintle 15.

The valve pintle 15 is of the four port hydrostatically balanced type, having two pairs of diametrically opposite ports as at 16, 16' and 17, 17' to provide for fluid distribution between the pump mains and rotary individual cylinders 33. Each pair of ports 16, 16', 17, 17' supply and discharge the fluid under the same pressures and it will be seen that the fluid at the working surfaces of the 55

pintle 15 will be in hydrostatic equilibrium with respect to the piston loads at all times.

The valve pintle 15 is further provided with a slightly tapered working section 15" in cooperation with a similarly shaped and fitted barrel bore 23 of the piston carrying rotor or barrel 25. The working section 15" is provided with small operating clearance, say one-half to one thousandth of an inch, adjacent the barrel bore in order to provide clearance space for lubricating fluid supplied as slip from the operating fluid of the pump. The small clearance space contrary to common journal mounting practice is not eccentric but concentric with the inner bore 23 of the barrel so that fluid may be drawn between the cooperative barrel and pintle surfaces not only by the dynamic action of rotation, but by the capillary attraction of the clearance space around the entire periphery of the pintle.

In order to maintain the aforesaid concentric clearance space for forced lubrication by capillary attraction, I provide double end supports for the large and small ends of the pintle, shown as needle bearing rollers 18 and 19 respectively in appropriate recesses 15' and 15"; (see Figs. 2 and 3). To facilitate the assembly of the pintle 15 with its double row of needle roller bearings in the barrel 25 I provide appropriate shoulders as at 15b and 15c respectively, so that when the needle rollers are packed with heavy grease they will stay firmly enough in their recesses to facilitate slipping the barrel over the pintle without disarranging the needles. For the proper functioning of my needle bearings 18 and 19, be it known, that contrary to the teachings of the prior art and prior bearing practice, I do not completely fill the recesses with the rollers but when the recess is full I take out one or two of the needles and temporarily fill the spaces left thereby with heavy grease so that when the needles are finally disposed between the pintle and cylinder barrel, there will be a definite predetermined clearance between the needles so that the capillary force will maintain and provide separator films between each pair of needles which film is substituted for the cages of anti-friction bearings of present commercial practice. Such present practice, using cageless rollers, advises packing the rollers tight so that there will be metal to metal contact between the adjacent needles and thus there is no space for a capillary oil film and, further, individual rotation of the rollers cannot take place. Contrary to the aforesaid practice, I provide a positive looseness and flexibility for the needle rollers for the above described purpose. The needles 18 and 19 being disposed in rotary contact with their respective races 15', 15" and the adjacent barrel bore surfaces are permitted flexibility of movement for the capillary action of the lubricating fluid, and the pump may be operated at a considerably higher speed than possible with pumps heretofore known.

In order to further assure not only perfect lubrication of the needles 18 and 19 in their recesses, but also lubrication and sealing of the working surfaces of pintle and barrel during the suction periods of the pistons and during low pressure operation of the pump respectively, when slip lubricant is reduced to an abnormal minimum, I provide a chamber as at 26', Figs. 2 and 3, to retain the slip fluid of the high pressure operating cycles for utilization during the low pressure cycles. In order to provide for the discharge of excess slip, I provide a pressure re-

lief valve comprising a valve seat 20, a ball check 21 and spring 22 assembled in appropriate axial bores of the barrel 25 including the chamber 27. When the chamber pressure reaches a predetermined value, measured by the compressive strength of the spring 22, the fluid under the ball will lift the ball, the fluid finally escaping from the chamber 27 through radial bores 28 in the barrel, (shown at the base of the impeller shaft portion 29).

It will be seen that under normal operation due to the pressure in chamber 26' a great part of the slip which has already passed the ports 16 and 17, 16' and 17' respectively into space 26' will be forced to flow in the opposite (left hand) direction in the clearance space between the pintle and barrel 25 and thus seal said clearance space against sucking of air as well as flood the working surfaces until the fluid reaches the needles of the bearing 18 where it will be retained in the spaces between the needles, effecting lubrication thereof, until the excess slip flow reaches the clearance space 65 around the pintle adjacent the left hand supporting means of the barrel.

The barrel 25 is provided with adjustable anti-friction bearing means as at 30—30, previously mentioned, in such manner that whereas the inner race members 31—31 of the bearings are rigidly secured to the respective ends of the rotor, 30 the outer race members 32—32 are axially adjustable respectively in the counter bore 10a of the body plate 10" and in the central opening of the cover plate 11. The purpose of the bearing adjustment is twofold. First when the pump 35 is new, pintle and cylinder fits are close and any binding at these surfaces may result in burning or scoring of the parts so fitted. During this period provision of a liberal number of shims as at 13 allows the bearings to operate freely, but after some operation of the pump when the pump appears to operate freely and function properly, some of the laminated shims may be removed from the shim assembly by removal of the plate 12. Upon replacement of the plate 12 the abutment flange 12b thereof axially shifts the outer races 32 in their respective bores taking up all play in the bearings and sometimes slightly pre-loading the bearings, meanwhile slightly adjusting the operative clearance space between the 50 pintle and cylinder at the frustro-conical working surfaces. It is evident that, by reason of provision for this bearing adjustment after considerable useful service and some wear, the pump may be reset for further long periods of service 55 in which both freedom of operation of the bearings and proper clearance between pintle and rotor obtain. The clearance space in the counter bore 24 adjacent the shoulder 15b, likewise the space 26', are ample to allow such slight axial 60 adjustment of the bearings 30 and the barrel 25 therewith as will ever be necessary.

Fig. 7 illustrates diagrammatically that when the pintle and barrel are adjusted relatively axially the clearance space is adjusted as by movement of the barrel from full line position at 25 (affording enlarged clearance space 23a) to dotted line portion at 25' (affording diminished space 23b).

The piston rotor or barrel 25 is further provided with a central web portion 34, a portion of which is shown in section at the top of Fig. 1, the web being cut away to form evenly distributed outwardly open radial guideways 35 for the piston crossheads 37 of radial pistons 36 operating 75

in cylinders 32 in the barrel. The piston cross-heads 37 are, as shown, integral with the radial pistons 36. Each piston crosshead 37 has a transverse bore which serves as the outer race for piston crosspin needle rollers 38 to rotatably support cross or roller pins 39 having, as shown, rollers 40-40 secured thereto for contact with the operating cam tracks as will be later described. The pistons with their integral heads, crosspins 38 and rollers 40 form a piston and thrust sub-assembly in which the needles 38 are retained in position by the rollers 40 themselves, all as more fully described and claimed in my copending application, Serial No. 726,962, filed May 22, 1934. The disposition of the needles in the piston cross-heads is the same as the disposition of the barrel needles 18 and 19, that is, the needles afford anti-frictional and capillary mountings for the supported elements, in this case the pins 39. Proper provision is made to secure antifrictional characteristics for the operation of needles 38 and capillary force feed lubrication thereof for the purpose of perfect lubrication of the pins 38 and to provide high speed bearing support for said pins in the crossheads 37. Since the driving of the piston rollers 40-40 upon their associated cam surfaces, indicated at 44, at commercial speeds is such as from 1000 R. P. M. to 2000 R. P. M., it is imperative to reduce not only rolling friction between rollers 40 and tracks 44 but provision must also be made to keep the axes of roller pins 39 parallel with the axis of rotation of the rotor 25. To eliminate substantial wear between the crossheads 37 and the guideways 35 of the web 34, the width of the web and of the crosshead is substantially wider than the diameter of the pistons. In keeping therewith large and heavy rollers are used to assure a positive contact simultaneously between the both rollers 40 of each pin 39 and their associated track 44 to provide free rolling contact therebetween. The large rollers are also an element in accomplishing the suction strokes of the pistons centrifugally and for fly wheel effect as will be later mentioned. The piston heads are circular in cross section adjacent their guideways 35 in order to allow slight rotation about the axes of the pistons, necessary for transverse alignment of the rollers during operation. Thus the speed and piston load will hold the rollers in continuous rolling contact with their respective tracks. Considering the enormous relative rotation of the rollers 40 driven by the rotor 23, when the rotor makes, say 1000 revolutions per minute, it is evident that in order to assure free true rotation between rollers 40 and tracks 44 it is necessary that the crosspins 38 freely rotate in the crosshead. The free rotation of rollers 40 thus assumes the free rotation of the respective pins 39, which again assumes the proper mounting of the pin. It was not possible heretofore to secure proper mounting for such high speed pins as 39 due to the lack of lubrication with ordinary antifriction bearings or sliding friction bushing bearings due to the great centrifugal force which tends to and does remove the lubricant from such bushings and from antifriction bearings which are packed tightly in their races. Due to the provision of adequate space between the needles such as will allow them to roll freely while still being small enough and of sufficient number to function as capillary retaining means for the lubricating fluid, the previous difficulties in supporting similar cross pins are overcome.

With the increased efficiency made possible by

the above described mountings etc. operation under much higher pressures was made possible but such higher pressures in conventional designs of pumps resulted in hydrostatic unbalance particularly at the working surfaces of the pintle and rotor and thus imposed a limitation to development along conventional lines using greatly increased pressures. To overcome this limitation, I have provided a two cycle pumping unit, wherein, during every revolution of rotor 25 each piston carries out two pressure and two suction strokes. Pumps of this kind heretofore known had no provision for variable discharge and suction and I have, therefore, designed a novel variable delivery cam mechanism having the desirable hydrostatic balance operating characteristics above referred to, which mechanism will now be described.

The cam mechanism (see Figs. 4, 5 and 6) comprises a pair of diametrically opposite circular members 41-41' and a pair of stationary members 46-46, the latter having straight planar working contours as at 58-58' and circular supporting surfaces adjacent the complementary inner surfaces of the casing.

The adjustable cam sections 41 and 41' have inner circular profiles as at 44 which support the rollers 40, and outer circular profiles as at 45 and 45' which serve as stops when the cams are in their maximum stroke positions (separated as shown in Fig. 1). In addition to the circular sections of the adjustable cams, these cams are provided with a pair of narrow rectangular rib portions as at 43 which serve as guides for the cooperative planar sided portions 35 47-47 (Fig. 3) of the stationary cams 46-46. The ribs 43 are closely fitted between the flat inner end surfaces of the casing and the portions 47 of the stationary cams, so that during the operation of the pump the composite cam 40 tracks 44-44' etc. may be varied in operative effect by shifting the circular members 41-41' as by means of control rods 42 and 42', see Fig. 3.

Fig. 5 shows the adjustable cams in position 45 such that the cam profiles 44 and 44' form an exact circle, and in this setting it is obvious that rotation of the barrel will cause no pumping action as the rollers 40 will merely revolve in a circle.

It will be seen that the cam members 41-41' have certain inherent advantages from the standpoint of manufacture due to their simple form. When the two parts 41 and 41' are finished at their adjacent ends as at 59, said parts may be fastened together as one body, and both track profiles 44 and 44' formed as one operation; likewise finished and ground.

It will be observed furthermore, that by means of a suitable spacer between the abutments 59, 60 Fig. 4, they may be clamped again to form virtually a one piece body to simultaneously turn and finish the outer circular surfaces 45, 45' which serve as stops by abutting the interior peripheral surfaces of the casing. This simple 65 method assures extreme accuracy and greatly reduces cost.

Referring to Fig. 6, an isometric view of one of the stationary cams 46, it will be seen that this part is formed with a cylindrical back to 70 precisely fit the cylindrical bore 61 of the main casing part 10 and a chordal flat portion 47 to form a continuation of the profiles 44 when separated as shown in Fig. 4. In order to avoid any shock or bump of the rollers, as these ride onto 75

and off the flat surfaces, it is imperative that the chordal track surface portions 47 of the stationary cams 46 be absolutely tangential to the semi-circles 44 and 44' of the adjustable cam members 41, 41'. Therefore, the adjustable track members slide directly on the members 46, 46' and the sliding surfaces in mutual contact are very accurately fitted. Since the surfaces 47 are stationary and parallel with the end covers of the casing as at 11a e. g., the rib portions 43 will be positively guided and supported so as to eliminate all vibration and tendency for the cam surfaces to get out of alignment.

It will be further observed that the stationary cams 46 are easily lined up with the parallel guide surfaces 58 of the adjustable members 41 about the cylindrical surface of the casing after which alignment dowel pins 51, (Fig. 3) may be fitted in place in both stationary cams to prevent rocking thereof consequent upon wear of the sliding surfaces. Figs. 1, 3 and 6 show that a circular recess 49 is cut in the central portion of the member 46 in order to clear the rotary web 34 of the cylinder barrel 25.

In operation of the pump, assuming the control members 42 are directly fastened to the adjustable cam members as at 60, the relative positions of these members determines the stroke of the pistons. The members 42 may be mechanically or manually or otherwise adjusted and/or locked, and the adjustment may be automatically effected in connection with other mechanisms as desired.

It will be noted that between the extreme stroke position Figs. 1 and 4 and the neutral position of Fig. 5 a continuous stroke adjustment for any desired stroke is possible without jerk or discontinuity of the pumping operation.

When the machine operates as a pump at commercial speed, such as earlier mentioned, the large mass of the piston and roller assemblies is sufficient to effect full suction strokes of the pistons, whereby I may eliminate from the structure expensive devices for positively moving the pistons outwardly. Thus, the large rollers are not only advantageous for the purpose of reducing track friction but they also provide the necessary suction strokes for the pistons and sufficient flywheel effect to the rotor to obviate the necessity for a separate flywheel.

It will be further seen that I have greatly improved the efficiency of the machine by the provision in the rotor of a fluid receiving chamber to store up fluid escaping as slip along the pintle, but also I have provided a relief valve which will build up pressure in the chamber, to thus force the slip fluid backward in the opposite direction and thus utilize it twice for lubrication. The excess of fluid in the chamber 26' will be relieved through the valve 21, when the built up pressure reaches the set pressure of the relief valve spring 22.

The working fluid will be properly distributed through ports 16, 16' and 17, 17' irrespective of the direction of the rotation of the pump. Reversal of the pumping action may be effected by the reversal of the direction of rotation of the impeller shaft. The pump may also be reversed by a 90 degree rotation of the cam mechanism by appropriate means (not shown). It will be seen that my cam mechanism is supported at all times on cylindrical surfaces in the casing, and upon cylindrical mating surfaces of the stationary cams 46; consequently it is clear that by an appropriate mechanism for effecting such 90 degree

rotation the adjustable cams and stationary cams may be adjusted to effect reverse pumping as a unit. The control means would, of course, also have to be rotated with the cam means in order to maintain proper control of the working fluid.

It will be further seen that in operation, due to the hydrostatic balance of fluid between the working surfaces of the pintle and cylinder barrel, the main bearings 30 of the latter will be practically unloaded. It will be easier to visualize the unloading of the bearings if we realize that in case of a 4 inch pintle, and hydrostatic unbalance the pintle load reacts on the barrel with an unbalanced area of at least $4'' \times 8'' = 32$ square inches, which creates a total of $32 \times 3000 = 96,000\#$ on the cylinder bearings, thus loading each of the bearings with $48,000\#$. This bearing load at $3000\#$ per square inch operating pressure would require two bearings, each capable of supporting a twenty-four ton load which requirement would be difficult to fulfill. If a partial balance would reduce above estimated bearing load to 50% of its full value, there is still a bearing load of twelve tons which requires a very strong bearing. From the above illustration, it will be seen that it is more important to unload the pump by my novel structure than to have a one piece adjustable eccentric in view of the fact that the replacement of non-hydraulic parts is much more simple and inexpensive than the replacement of hydraulic parts such as pistons and cylinders, pintle and barrel, for the simple reason that whereas the hydraulically functioning parts are closely and individually fitted together and are not interchangeable for manufacture, the mechanically functioning parts are more or less interchangeable and their replacement and cost is much lower than the replacement of hydraulically functioning parts.

While the reliable and efficient functioning of the device is assured by the compactness and simplicity of the device it must be remembered that the speed ratios between the rotating roller pins in the needle rollers and the rollers on their tracks are of equal importance. It is evident from the design that the needles 38 are compelled to rotate about their own axes with enormous speed in order to maintain rolling contact between the roller and their race members and it was previously believed impossible for any anti-friction element to carry out such high speed rotation about individual axes when the load is so great as $3000\#$ per each square inch of piston area. However, I have found that by maintaining the same speed ratio between rollers and track as between roller pins 39 and needles 38, the needles will carry their loads without being damaged. In the present structure for every revolution of the rotor the rollers 40 will have the same number of individual rotations as the needles 38 about their axes. A ratio analysis of the disclosure hereof (neglecting the elliptical shape of the tracks 44) shows that the ratio between cross-pin and needle diameter is the same as the ratio between track diameter and roller diameter.

Various changes may be made in the details of the pump without departing from the scope of the inventive idea as defined in the appended claims.

The present application is limited to the specific reactance means described, the broader principles of the invention being claimed in my copending application Serial No. 749,746, filed October 24, 1934.

I claim:

1. In a hydraulic pump or motor of the rotary radial plunger type, including a casing, a rotatable barrel, a plurality of plungers carried by the barrel, a radial flange on the barrel in the zone of the plungers, radial guideways in the flange for the plungers, reactance engaging means on the plungers respectively and disposed alongside both faces of the flange, adjustable reactance means disposed along both faces of the flange and providing a continuous reactance track for the reactance engaging means in all adjusted positions of the reactance means, said reactance means including a pair of symmetrical reactance elements diametrically opposite to each other and adjustable toward and away from the axis of rotation of the barrel, each of said reactance elements having two axially spaced curved track portions, the track portions of one element defining without track portions of the other element continuous curved tracks coaxial with the barrel when the elements are adjusted to their innermost position, means mounted in the casing and having track portions tangential to the track portions of the elements and arranged to bridge the spaces between the adjacent ends of the track portions of the elements when the elements are separated and to form with said curved track portions continuous tracks, said track portions of said last named means being spaced apart axially of the barrel and accommodating the outer marginal portion of the flange therebetween.
2. In a hydraulic pump or motor of the rotary radial plunger type, including a casing, a rotatable barrel, a plurality of plungers carried by the barrel, a radial flange on the barrel in the zone of the plungers, radial guideways in the flange for the plungers, reactance engaging means on the plungers respectively and disposed alongside both faces of the flange, adjustable reactance means disposed along both faces of the flange and providing continuous reactance tracks for the reactance engaging means in all adjusted positions of the reactance means, said reactance means including a pair of symmetrical reactance elements arranged diametrically opposite to each other and adjustable toward and away from the axis of rotation of the barrel, each of said reactance elements having two axially spaced curved track portions defining continuous curved tracks coaxial with the barrel when the elements are adjusted to their innermost position, bearing blocks in the casing having chordal bearing surfaces, complementary surfaces on the said elements and in engagement with the said chordal surfaces for supporting the elements for said adjustment, said blocks having chordal track surfaces tangential to the track portions of the elements and arranged to bridge the spaces between the adjacent ends of the track portions of the elements when the elements are separated from each other and supported on the chordal bearing surfaces, and to provide with said curved track portions continuous tracks for the reactance engaging means, and each of said blocks having a groove disposed between the chordal track surfaces thereof for accommodating the outer marginal portion of the barrel flange as the barrel rotates.
3. In a hydraulic pump or motor of the rotary radial plunger type, including a casing, a rotatable barrel, a plurality of plungers carried by the barrel, a radial flange on the barrel in the zone of the plungers, radial guideways in the flange for the plungers, reactance engaging means on the plungers respectively and disposed alongside both faces of the flange, adjustable reactance means disposed along both faces of the flange and providing continuous reactance tracks for the reactance engaging means in all adjusted positions of the reactance means, said reactance means including a pair of symmetrical reactance elements arranged diametrically opposite to each other and adjustable toward and away from the axis of rotation of the barrel, each of said reactance elements having two axially spaced curved track portions defining continuous curved tracks coaxial with the barrel when the elements are adjusted to their innermost position, bearing blocks mounted in the casing and having chordal bearing surfaces at their lateral margins, chordal bearing surfaces on the elements complementary to those of the blocks for supporting the elements, said elements being reduced in width adjacent the blocks, chordal raised portions on the blocks received between the reduced width portions of the elements and lying alongside thereof and having track surface portions tangential to the curved track portions and forming continuous tracks with the curved track portions when the elements are separated, and said reactance engaging means spanning said reduced width portions and adjacent track portions of the blocks.
4. In a hydraulic pump or motor of the rotary radial plunger type, including a casing, a rotatable barrel, a plurality of plunger and cylinder assemblies carried thereby, adjustable reactance means therefor providing a continuous reactance path for the assemblies in all adjusted positions, said means including a pair of reactance elements having semi-circular reactance track portions arranged diametrically opposite to and symmetrically with respect to each other, said elements being adjustable toward and away from the axis of rotation of the barrel to different adjusted positions for adjusting the strokes of the assemblies, the reactance track portions defining a continuous circular track coaxial with the barrel when the elements are adjusted to their innermost position, said elements having outer abutment surfaces defining a cylindrical surface coaxial with the barrel when the elements are adjusted to their outermost relative position, said casing having a cylindrical wall in the plane of the elements and surrounding the same and having the same radius as the said cylindrical surface of the elements and coaxial with the barrel, whereby the elements are rigidly supported against hydraulic load by the casing wall, and means in the casing bridging the space between the ends of the semi-circular track portions of the elements when the elements are separated and forming with said semi-circular track portions a continuous closed track.
5. In a hydraulic pump or motor of the rotary radial plunger type, including a casing, a rotatable barrel, and a plurality of plunger and cylinder assemblies carried thereby, valve means for the assemblies, adjustable load reactance means for the assemblies providing a continuous path for the assemblies in all adjusted positions of the reactance means, said load reactance means including a pair of separable elements arranged diametrically opposite to each other and said elements being movable toward and away from the axis of rotation of the barrel and having symmetrical curved load reactance track portions defining a continuous track when the elements are adjusted to their innermost position, said elements terminating in end to end relation and

- being in end to end abutting relationship when adjusted to their innermost position and having slots opening through their ends, said slots being tangential to the track portions of the elements adjacent the ends of the elements, and separate load track means mounted in the casing and having chordal track portions respectively accommodated in said aligned slots and bridging the space occasioned between the elements consequent upon separation of the elements, said chordal portions extending to the reactance track portions of said elements and defining tangential load reactance track portions between the curved track portions of the elements when the elements are separated.
6. In a hydraulic pump or motor of the rotary radial plunger type, including a casing, a rotatable barrel, and a plurality of plunger and cylinder assemblies carried by the barrel, valve means for the assemblies, adjustable reactance means for the assemblies providing a continuous reactance track for the assemblies in all adjusted positions of said reactance means, said means including a pair of symmetrical separable reactance elements arranged diametrically opposite to each other and movable toward and away from the axis of rotation of the barrel, said elements having symmetrical curved reactance track portions defining a continuous load reactance track coaxial with the barrel when the elements are in their innermost adjusted position, supporting means for the elements mounted in the casing, said supporting means having slide bearing surfaces in sliding engagement with the elements adjacent the ends of the elements for supporting and guiding the elements during adjustment thereof and having chordal portions bridging the space occasioned between the elements consequent upon separation of the elements from each other, said chordal portions extending to the reactance track portions of the elements, and defining tangential load reactance track portions between the track portions of the elements when the elements are separated.
7. In a hydraulic pump or motor of the rotary radial plunger type including a casing, a rotatable barrel, and a plurality of plunger and cylinder assemblies carried thereby, valve means for the assemblies, adjustable reactance means for the assemblies in all adjusted positions of said reactance means, said reactance means including a pair of symmetrical separable reactance elements arranged diametrically opposite to each other, each element being movable toward and away from the axis of rotation of the barrel, said elements having reactance track portions defining a continuous track when the elements are adjusted to their innermost position, said casing having an inner cylindrical wall coaxial with the axis of rotation of the barrel, bearing blocks for the elements having cylindrical back surfaces mating with the cylindrical wall of the casing and having chordal inner bearing surfaces respectively, said elements having outer chordal bearing surfaces adjacent their ends, the chordal surfaces of each block engaging the chordal surfaces of the adjacent ends of the elements for slidably supporting the elements in the casing, means on the blocks for bridging the space occasioned between the elements consequent upon separation of the elements and defining reactance track portions between the track portions of the elements when the elements are separated, and said elements having cylindrical back surfaces of the same radius as the cylindrical casing wall and fitting the casing wall when the elements are moved to their outermost position, whereby the entire reactance track is directly supported by the casing wall during maximum stroke.
8. In a hydraulic pump or motor of the rotary radial plunger type including a casing, a rotatable barrel, a plurality of plunger and cylinder assemblies carried thereby, valve means for the assemblies, adjustable reactance means therefor, said reactance means including a pair of diametrically separable load reactance track elements, parallel guide means carried in the casing and engaging said elements and supporting the same for radial movement toward and away from each other to change the contour of the track, said reactance elements having outer cylindrical surface portions, and said casing having internal cylindrical surface portions coaxial with the barrel and surrounding and complementary to and fitting the cylindrical surface portions of the reactance elements respectively, and co-extensive therewith, when the elements are moved a maximum distance apart, whereby upon separation of the elements to the extreme separated position, the complementary surfaces of the elements and casing engage and each element is fully supported by the casing for resisting hydraulic load.
9. In a pump or motor of the radial piston type, a rotatable barrel, a plurality of plunger and cylinder assemblies carried thereby, valve means for the assemblies, adjustable reactance means comprising two fixed straight load track members oppositely disposed with respect to the carrier axis, and two adjustable load track members supported on and slidable with respect to the fixed track members and disposed opposite to each other between the fixed tracks, each adjustable track member having a curved track surface the ends of which terminate in tangential relation to the fixed track members to form therewith a complete rigid track annulus of variable dimensions symmetrical about the carrier axis, and means on the plungers in rolling engagement with said annulus to reciprocate the plungers.
10. In a pump or motor of the character described, a casing, a valve pintle rigidly secured therein, a rotor rotatably mounted in said casing and having a central bore receiving the valve pintle, a radial flange on the barrel and having radial guideways, cooperative ports between said barrel and pintle, radial pumping units carried by said rotor and guided respectively in said guideways, reactance means surrounding said rotor and supported by the casing, actuating devices for the said pumping units operated by said reactance means, said reactance means including pairs of curved load track elements, the elements of each pair being spaced axially of the rotor from each other and accommodating the flange therebetween, and said pairs being adjustable radially toward and away from each other, and a pair of stationary planar load track elements having track portions at each side of the flange, said track elements conjointly forming continuous parallel load tracks at opposite sides of the flange and, variable in operating effect, by adjustment of the curved tracks.
11. In a pump or motor of the character described, a casing having a cylindrical wall, a rotor rotatably mounted in said casing, a radial series of pumping units including pistons driven by the rotor, valve means therefor, reactance means surrounding the rotor and supported by

the casing, said means including a pair of adjustable separable members having curved working contours, piston actuating devices for the pistons of said pumping units and operated by said reactance means, means associated with said reactance means for moving the adjustable members toward and away from each other to change the working contour of said reactance means symmetrically on opposite sides of the rotor axis and to thereby change the stroke of the pistons, said reactance means including a pair of diametrically opposite stationary members having cylindrical back surfaces in mating relation with said cylindrical casing and supported thereby, and track surfaces cooperating with the piston actuating devices, the track surfaces providing continuations of the working contours of said adjustable members in all adjusted positions thereof to form therewith a continuous track for the piston actuating devices.

12. In a hydraulic pump or motor of the rotary radial plunger type, including a casing, a rotatable barrel, a plurality of plunger and cylinder assemblies carried thereby, valve means for the assemblies, adjustable reactance means therefor providing a continuous reactance path for the

assembly in all adjusted positions, said means including a pair of separable reactance elements having reactance track portions arranged diametrically opposite to and symmetrically with respect to each other, said elements being adjustable toward and away from the axis of rotation of the barrel to different adjusted positions for adjusting the strokes of the assemblies, the reactance track portions defining a continuous track surrounding the barrel when the elements are adjusted to their innermost position, means in the casing bridging the space between the ends of the track portions of the elements when the elements are separated and forming with the said track portions of the elements a continuous closed track, substantially the entire back surfaces of the elements providing abutment surfaces of the elements, and said casing having a wall in the plane of the elements and surrounding the same and fitting the abutment surfaces of the elements when the elements are adjusted to their outermost separated position, whereby the elements are rigidly supported against hydraulic load by the casing wall.
